SIGNALING SYSTEM FOR TOY RAILROADS

Philip C. Bagnasco, Williston Park, N. Y.

Application October 20, 1938, Serial No. 235,943

1 Claim. (Cl. 246—31)

This invention relates to improvements in signaling systems and has particular reference to a block signaling system for toy electric railroads.

An object of the invention is to provide an improved system of simple and practical construction wherein a series of signals of different characteristics at each of two or more stations are automatically controlled by the positions of trains on the trackway of the system, and in which the speed of a train approaching any station may be regulated in accordance with the signals set at said station.

The inventive idea involved is capable of receiving a variety of expressions some of which, for purposes of illustration, are shown in the accompanying drawings, wherein:

Figure 1 is a fragmentary diagrammatic view of the circuits and apparatus for carrying out the invention.

Figure 2 is an enlarged diagrammatic view of the circuits and apparatus at one of the stations of the system.

Figure 3 is a fragmentary elevation of a rail and contact member carried by the truck of the toy locomotive.

Figure 4 is a top plan view, partly broken away and shown in section, of the apparatus at one of the stations.

Figure 5 is a vertical longitudinal section through the apparatus of Fig. 4, and,

Figure 6 is a perspective view of a modified form of rail contact member employed in the system.

The system illustrated in the drawings comprises a trackway consisting of the two wheel rails 10, 11 and a third rail 12 from which the motor of a toy railroad train receives its current for operation. It may be assumed that the truck 13 (Fig. 1) carries the locomotive of a train and, in conjunction with this truck, there is provided a contact member 14 carrying the rollers 15 which engage said third rail for the purpose of conveying current to the motor of the train. For convenience in illustration, the trackway is shown in a straight line but it will be understood, of course, that the same may take a circular or other form. The trackway is, like in standard practice, made up of a plurality of sections capable of being joined together to form the complete trackway. Two or more signaling stations may be associated with the trackway depending upon the length thereof, and, as shown in Fig. 1, two such stations A and B are shown at separated points. The trackway is divided into blocks two of which are indicated at

A1 and B1, with the station A controlling the signals for block A1 and station B regulating the signals for block B1 and also controlling certain signals at station A. The blocks are determined by insulated sections 16 and 17 of the third rail 12, said sections being associated with the stations A and B, respectively.

The apparatus which is included in each of the signaling stations proper is illustrated in Figs. 4 and 5 as comprising a base 18 upon which is mounted a cover 19 and a signal tower 20 the casing 21 of which has disposed therein the three visible signals 22, 23 and 24 which may be green, amber, and red, respectively. An insulated extension 25 of the base 18 projects therefrom beneath the rails 10 and 12 and carries clamps 26 at its outer end engageable with the third rail 12 so as to cooperate with an eccentric locking lever 27 carried by the extension 25 and engageable with the track 10 for securing the base 18 in fixed relation to the trackway.

Enclosed within the cover 19 and supported upon the base 18 is a plate 28 which carries two pairs of electromagnetic devices, such as solenoids 29, 30 and 31, 32. The solenoids of the two pairs are opposed to each other and have the common cores 33, 34, respectively, provided with laterally extending pins 35 and 36. A switching device is associated with each pair of solenoids for controlling various operations of the system. The device which operates in conjunction with the solenoids 29, 30 includes a bracket 37 in which is rockingly mounted a movable contact 38 in the form of a bell crank lever, with one of the arms thereof engageable with the fixed contact 39 and the other arm adapted for engagement with the fixed contact 40 when said movable contact 38 is alternately rocked about its pivot in opposite directions by engagement of the pin 35 with the then vertical arm of said movable contact. Said operation occurs when either one of the solenoids 29 or 30 is energized to move the core 33 in the desired direction. The switching device associated with the solenoids 31, 32 is of similar construction and includes the locking switch contact 41 adapted to be actuated by the pin 36 for alternate engagement with the pairs of fixed contacts 42 and 43.

In addition to the above described apparatus, means are associated with station B, which may be designated as the control station as distinguished from station A, for controlling certain signals at both stations and for also governing the condition of the third rail 12. Such means embodies the insulated sections 44 and 45 (Fig.

1) arranged at suitably spaced intervals along the trackway beyond station B, each of said sections being bridged by conductors 46. As shown in Fig. 6, the insulated sections on the rail 12 5 may take the form of a contact shoe 47 in the nature of a clip mounted upon said rail and electrically separated therefrom by the strip of insulation 48. Such a construction permits of the shoe 47 being adjusted to various points along 10 the rail 12 so as to vary the timing of the operations to be performed by said shoes in accordance with the length of the trains on the trackway. For example, it may be desired that the 15 operation to be performed by the first contact element beyond the station B, which element has its equivalent at 44 (Fig. 1), shall not occur until the last car of the train has moved beyond the insulated section 17 at station B. This result may be accomplished by adjusting said contact shoe 47 to a distance from the section 17 20 equal to the length of the longest train being operated. In the same sense, when an adjustable contact 47 is employed at the section 45, the same may be spaced any desired distance from 25 the insulated section 44.

The operation of the system will now be described. Under the assumption that a train is approaching the signaling station A and is in block A1, and that a preceding train has cleared 30 block B1, the green signal 22 at station A is illuminated so that the first train may proceed into block B1. By reference to Fig. 2, which shows the diagram for the circuits at station A as well as at station B, it will be seen that under the 35 above named condition a circuit is established for the lamp 22 extending from the positive side of battery 49 through the conductor 50, the movable contact 38, the fixed contact 39, the movable contact 41, the upper fixed contact 42, the lamp 22, 40 and from thence to ground through the grounded plate 28, the conductor 51 joining said plate with the rail 10, and back to the other side of battery through the conductor 52 also connected to said rail. A branch of said circuit also extends from 45 the movable contact 41 through the lower fixed contact 42 and the conductor 53 to the third rail 12 which is thus energized with the full voltage from the battery 49 to operate the motor of said first train. When the contact element 14 of the 50 train truck 13 bridges the energized third rail in block A, the green signal 22 at said station is extinguished, the red signal is lighted, the third rail in block A1 is deenergized and the amber signal 23 at the preceding station (not shown) is 55 illuminated. The bridging of said rail 12 and the section 16 continues the previously described circuit from the conductor 53 through the contact element 14, the conductor 54 connected to the insulated section 16, and from thence in one direction through the conductor 55 through the winding of the solenoid 29 back to the other side of battery 49 through the conductors 51 and 52. Said circuit is established in another direction from the conductor 54 through the conductor 56, 60 the terminal post 57 and conductor 58 back to said preceding signaling station where the solenoids 38 and 31 are energized, in a manner to later appear, to light the amber lamp 23 at the latter station. The energization of the solenoid 29 moves the 65 core 33 to the left, as shown in Fig. 2, thereby causing the movable contact 38 to be disengaged from the contact 39 and engaged with the contact 40. When so engaged the circuit for the red signal 24 is established through said contacts 38, 40 70 and the lamp 24 over the previously described 75

path back to the negative side of the battery 49. The switching of said contact 38 from contact 39 also removes the source of electrical energy from the third rail of block A1 so that a following train will be stopped should it enter said block. 5

With the above conditions existing, the first train moves through block B1 and when its contact element 14 bridges the third rail of said block and the insulated section 17 the same operation as previously described takes place with the result that the signal at station B is changed from green to red, the third rail in block B1 is deenergized, and the amber lamp 23 at station A is illuminated by energization of the solenoids 30 and 31 through the circuit including the conductors 56 and 58. The effect of the energization of said solenoids at station A will be described by reference to Fig. 2 which is illustrative of the control circuits at said station. It will be recalled that before the first train reached station B, the red signal at station A was illuminated with the contacts 38 and 40 in engagement and the contact 41 in the position shown in Fig. 2. However, when said circuit through the conductor 58 and the windings of the solenoids 30 and 31 at station A is established, said solenoids are simultaneously energized to move their respective cores 33 and 34 in opposite directions with the result that the contact 38 at station A is restored into engagement with the contact 39, and the contact 41 is operated to engage the contacts 43. A circuit is thereby closed from the battery 49 through contacts 38, 39, contact 41 and upper contact 43 to ground through the lamp 23. Also, through the lower contact 43, battery is connected to the variable resistance 59 and conductor 53 to the third rail of block A1. This variable resistance 59 reduces the voltage now connected to said third rail with the result that any following train entering block A1 will have its speed reduced in accordance with the decrease in said voltage, and this decreased speed of the train will be continued until the then existing condition of the third rail in block A1 is altered. The movable contact 38 at station B having been disengaged from the contact 39, the battery 49 is disconnected from the third rail in block B1 and said rail is deenergized. 45

As the first train proceeds from this point and preferably after the last car of said train passes over the insulated section 17 the contact element 14 bridges the insulated section 44, or engages with the adjustable insulated contact 47 (Fig. 6). A circuit is thereby established from the positive side of battery 49 through the conductor 60, the third rail 12, contact element 14, section 44, conductor 61, and the windings of solenoids 31, 30 and back to battery through the conductors 51 and 52. Said solenoids are simultaneously energized as previously described with the result that contact 38 is reengaged with contact 39 and contact 41 is engaged with contacts 43. In a manner now obvious, the red light 24 at station B is extinguished, the amber light 23 is illuminated and the battery 49 is connected through contacts 65 41, 43 and resistance 59, to the third rail 12 in block B1 so that a following train entering said block will have its speed reduced. At the same time, the circuit for energizing the solenoids 31, 30 is also extended through the conductor 62 to 70 the terminal post 63 and from thence over the conductor 64 to the solenoid 32 at station A, and from thence to battery with the result that solenoid 32 is energized to light the green lamp 22 at station A in the same manner as will presently 75

appear in connection with the description of the operation at station B.

The first train now proceeds until it reaches the insulated section 45 positioned at a suitable distance from section 44. Upon bridging of the third rail and said section 45, the circuit through the conductor 60 and said third rail is continued over the conductor 65 and through the solenoid 32 at station B to ground and back to the other side 10 of battery 49 through conductors 51 and 52. The solenoid 32 is thus energized to rock the contact 41 out of engagement with the contacts 43 and into engagement with the contacts 42. Whereupon, with contacts 38, 39 engaged by the previous 15 energization of solenoid 30 the originally described circuit for the green lamp 22 is established and full voltage is applied from the battery 49 to the section of the third rail in block B1 so that if a following train is now in said block its speed 20 will be increased.

What is claimed is:

In a toy railroad signaling system, a trackway and a third rail, said third rail having short, spaced, insulated control sections to form a plurality of blocks along said third rail, a source of electric energy for supplying current to said trackway, to said blocks and to each of said short insulated sections, a signal station for each of said blocks, signals at each of said stations, a plurality of electromagnetic devices including

switching means which remain in their last operated position when deenergized at each of said stations and which are connected to said control sections for variously controlling said signals, the switching means of said electromagnetic devices also connecting said source to and disconnecting the same from the block in the rear of the associated station, means including the control section at each of said stations for controlling one of the signals at the preceding station through the 10 electromagnetic devices thereat, a separate short insulated section in said third rail beyond the last signal in advance of one station and connected to a first one of the electromagnetic devices thereat and to a different one at the preceding station 15 for controlling one of the signals at the former station and for also controlling a different signal at said preceding station, and additionally controlling said switching means through said electromagnetic devices, and a second separate 20 short insulated section in said third rail beyond the first named separate section and connected to a second electromagnetic device at said former station for controlling still another signal thereat, 25 all of said short insulated sections being energized by the passage of a train thereover whereby said electromagnetic devices will be temporarily energized.

PHILIP C. BAGNASCO.
